UNITED STATES PATENT OFFICE.

JAMES T. CALLANAN, OF PARKERSBURG, WEST VIRGINIA, ASSIGNOR TO
THE PARKERSBURG MACHINE COMPANY, OF PARKERSBURG, WEST
VIRGINIA, A CORPORATION OF WEST VIRGINIA.

SOFT-METAL WALL-PACKER.

No. 823,760.

Specification of Letters Patent.

Patented June 19, 1906.

Application filed October 12, 1904. Serial No. 228,220.

To all whom it may concern:

Be it known that I, JAMES T. CALLANAN, a citizen of the United States, residing at Parkersburg, in the county of Wood and 5 State of West Virginia, have invented certain new and useful Improvements in Soft-Metal Wall-Packers, of which the following is a specification, reference being had therein to the accompanying drawings.

10 This invention relates to packers for shutting off water, &c., in deep oil and gas wells, and the primary object is to provide a packer wherein lead or other soft metal may be substituted for rubber, which is now universally used for making the water-excluding seal.

15 A further object is to provide a packer with compression-heads of improved form especially adapted for expanding the soft-metal packing material.

20 In the accompanying drawings, Figure 1 is a vertical sectional view of my improved packer before it has been expanded, and Fig. 2 is a similar view showing the same expanded.

25 Referring to the drawings, 2 designates a tubular head forming the upper end of the packer, which is secured to the lower end of well-tube 3. Depending from head 2 is the tubular packer-body 4, which extends 30 through bottom head 5, the lower extremity of the body being outwardly flanged at 4' to underhang downwardly-facing shoulder 6 in the lower portion of head 5. Below shoulder 6 the head is formed with a depending internally-threaded rim 7, and uniting with the latter is the tubular member 8, into which the packer-body lowers when the packer is expanded, as in Fig. 2. A reducer 10 at the lower extremity of portion 8 serves to connect anchor-tube 11, which extends to the bottom of the well.

35 Surrounding packer-body 4 is a sleeve or annulus 9, of lead or other soft metal, which is normally of the same diameter as heads 2 and 5, between which it is confined. The lower portion of head 2 tapers inwardly and downwardly, as shown at 2', where it is embraced by the upper end of the soft metal, said sloping or tapering extremity being interrupted by annular groove or notch 2'', which interlocks with and secures a firm hold on the metal. The inner or upper end 5' of bottom head 5 is similarly tapered and em-

braced by the lower end of the soft-metal sleeve. 55

In operation the metal sleeve retains the shape indicated in Fig. 1 until force or pressure is applied in such manner as to contract the space between heads 2 and 5. In placing the packer in position anchor-tube 11 is of 60 such length as to rest on the bottom of the well and position the packer at the point where it is desired to locate the same. The anchor-tube thus forms a positive support for bottom head 5, and the weight of the 65 string of tubing on upper head 2 causes the latter to move downward, as such movement is resisted only by the soft metal, the packer-body 4 being free to lower into portion 8, as in Fig. 2. The lead or other soft 70 metal is thus caused to spread laterally against the wall of the well and to so flow as to solidly fill the space between the latter and packer-body 4, as shown in Fig. 2. While the spreading of the metal is materially assisted by the tapered heads, the invention is not restricted to the latter, as the metal would flow and pack in substantially the same way if the heads were of different form. It is characteristic of lead and other soft 80 metals that when subjected to pressure they will so flow as to solidly fill the spaces in which they are confined, and this principle is availed of in the present invention for providing an absolutely solid packing. It is in 85 this essential particular that the invention differs widely from the well-known types of packers, in each of which the packing material consists of a rubber sleeve. When subjected to pressure, the rubber sleeve is expanded or 90 forced outward at one or more points in its length into engagement with the well-wall; but it is well known that the action of rubber when under pressure is such that it cannot be caused to flow and so change its form as to 95 solidly fill the space to be packed. Furthermore, as lead is indestructible the improved packer is absolutely permanent, whereas rubber deteriorates and must in time be replaced.

95 Although the improvement is here shown 100 and described as packer for well-tubing, it will be understood that it may be used as a casing-packer with equal effect.

I claim—

105 1. In a wall-packer, the combination of a packer-body, separated heads on the packer-

body, one movable toward the other, the end of one of said heads being reduced and notched, and a sleeve of soft metal surrounding the packer-body between the heads and 5 embracing the said reduced and notched head end.

2. In a wall-packer, the combination of a packer-body, a sleeve of soft metal surrounding the body, two oppositely-tapered packer-10 heads at opposite ends of the sleeve, the tapered ends of the heads being embedded in

the soft metal, one of the heads being formed with a notch to interlock with the soft metal, and means for moving one of said heads toward the other. 15

In testimony whereof I affix my signature in presence of two witnesses.

JAMES T. CALLANAN.
